CLAIM

The ornamental design for a stand alone universal dock/charger for a portable electronic device, as shown and described.

DESCRIPTION

FIG. 1 is a perspective view of a stand alone universal dock/charger for a portable electronic device, embodying my new design;

FIG. 2 is an alternate perspective view thereof;

FIG. 3 is a front elevation view thereof;

FIG. 4 is a rear elevation view thereof;

FIG. 5 is a side elevation view thereof;

FIG. 6 is a top plan view thereof; and,

FIG. 7 is a bottom plan view thereof.

The broken line showing of the electronic device in FIG. 1 is included for the purpose of illustrating environment of the article, while all other broken lines shown are included for the purpose of illustrating the unclaimed portions of the article; all of the broken lines form no part of the claim.

1 Claim, 6 Drawing Sheets
